UNITED STATES PATENT OFFICE

2,562,899

PNEUMATIC DECK SCALING MACHINE

Daniel J. Finn, Everett, Mass.

Application August 8, 1946, Serial No. 689,133

1 Claim. (Cl. 29—81)

(Granted under the act of March 3, 1883, as
amended April 30, 1928; 370 O. G. 757)

1

The present invention relates to apparatus for removing scale from steel decks and the like.

Preparatory to applying new paint or preservative to steel decks of ships, oil tanks, and the like, it is necessary to remove the old paint and scale which has accumulated from corrosion. Heretofore, this scale has been chipped loose by the use of either hand actuated chipping hammers or scrapers or small pneumatic chippers held in the hand of an operator. The task of cleaning large areas by this method is very slow and tedious, besides being injurious to the respiratory system of the operator in view of the necessary proximity of the operator to the flying scale which is chipped loose. The use of pneumatic air hammers also results in uneven chipping, due to varying pressure applied to the hammer by different operators. Even after chipping is completed by this method additional buffing and finishing is required before paint can be applied to the surface.

Accordingly, the primary object of the present invention is to provide an improved scaling machine.

A further object of the present invention is to provide a scaling machine which will speed up the scaling process.

Another object is to provide a machine which will perform a uniform scaling operation on steel decks and the like.

A still further object is to provide a machine for scaling steel decks and the like in operation of which the operator of the machine will be protected from the scale being chipped.

The foregoing and other objects of the present invention will be apparent from the detailed description when taken with the accompanying drawings in which:

Fig. 1 is a generally perspective view of one embodiment of the present invention;

Fig. 2 is a perspective view of the underside of the embodiment of the invention shown in Fig. 1; and

Fig. 3 is a sectional view of a conventional pneumatic chipper of the type employed in the present invention.

The machine herein described comprises essentially a movable vehicle upon which are mounted a plurality of pneumatic chippers, the chippers being so disposed on the vehicle that a strip of surface substantially the width of the vehicle is scaled as the vehicle is pushed along.

The chipping hammers used in the present invention are preferably of the conventional hand type as illustrated in Fig. 3 and comprises essentially a cylinder 10, a piston 11, a cylinder head 12, and a chisel 13. In the usual operation of the chipper a throttle lever 14, a throttle valve

2

15, and associated springs and pins for actuation of the throttle valve are necessary, but in the present application of the chipper the throttle valve and its actuating means are removed to 5 allow operation of the hammer as soon as compressed air is applied through the cylinder head at point 16. The operation of the chipper is familiar to those versed in the art so a discussion of its operation is not considered necessary here. 10 The chisel 13 can be removed from the hammer when it becomes worn, thus providing ease in servicing the present machine.

The vehicle on which the air hammers are carried comprises essentially a rectangular frame 20, Fig. 1 and Fig. 2, preferably fabricated from angle iron, and four wheels 21 attached to axles 22 to support frame 20 substantially as shown. A handle 23, preferably of tubular stock, is rigidly attached at the rear of frame 20 and extends 20 backward and upward to such a height that the vehicle can be conveniently pushed by an operator when in a standing position. Attached to frame 20 and disposed so as to be parallel to axles 22 are two plate members 24 and 25 spaced 25 substantially as shown. Plates 24 and 25 have holes cut through them to engage the lower end of the cylinder 10 of the pneumatic chippers. In the present embodiment of the invention plate 24 has three holes symmetrically disposed with respect to the ends of the plate, with a spacing between centers substantially equal to twice the width of the blades of chisel 13 of the pneumatic chipper. Plate 25 has four holes symmetrically disposed with respect to its ends and spaced similarly as the holes in plate 24. The holes are of 30 such shape and size that they engage snugly the chisel end of cylinder 10, which has flattened sides for a short way up the walls of the cylinder. The shoulder which is formed by the transition from the flat sides to a full cylinder rests on the tops of plate 24 and 25 and thus supports the chippers and prevents rotation of the cylinders. The shape of the lower end of cylinder 10 is clearly shown 35 in Fig. 2. The chippers are mounted in the plates such that the blades of chisels 13 are normal to the axis of motion of the machine. It is apparent that as the machine is pushed over the deck, the chisels extending from plate 25 engage the area missed by the chisels in plate 24. 40 The wheels 21 of the vehicle, of course are of such diameter that chisels 13 contact the deck with sufficient pressure to perform the chipping operation when air is applied to the chippers. The present embodiment shows a machine with 45 seven chippers installed, but it is apparent that any desired number may be used so long as they are spaced to insure complete coverage of the area beneath the machine as it is pushed along.

3

Plates 26 and 27 with holes spaced identically with the holes of plates 24 and 25, respectively, engage the cylinder heads of the chippers to maintain them in vertical alignment. The holes in plates 26 and 27 are countersunk to fit the conical portion of cylinder head 12 of the chipper. A slight vertical movement of the cylinders 10, while the chippers are in operation, is allowed by the extension of four extension springs 30, which are secured between upper plates 26 and 27 and lower plates 24 and 25 by stub bolts 28 and nuts 29. Should the tension of springs 30 be insufficient to maintain vertical alignment of cylinders 10, guide bolts may be used between the upper and lower plates to add rigidity to the system.

At point 16 of the chippers (Fig. 3) are inserted stub pipes 31 to which are attached by suitable coupling means 32 flexible tubes 33. A manifold 34 which is essentially a large pipe closed at both ends, or similar cylinder, is mounted on plate 35, which in turn is supported by frame 20, with its axis normal to the axis of motion of the machine. Seven stub pipes 36 symmetrically disposed with respect to the ends of manifold 34 and equally spaced are inserted through the walls of manifold 34. Each of stub pipes 36 are connected by flexible hoses 33 to its respective stub pipe 31 to provide a free passage for air from the manifold 34 to the piston 11 (Fig. 3) of the pneumatic chipper. Another flexible hose 37 is connected to one end of the manifold by suitable plumbing 38 and extends along handle 23 to a throttle valve 39 attached to handle 23 in convenient reach of the operator. Supply hose 40 which enters the throttle valve is connected to a supply of compressed air of pressure suitable for operation of the type of air hammers used, and should be of sufficient length to allow free movement of the machine about the deck or surface being worked upon.

In operation, compressed air enters the manifold 34 through hose 37 when throttle valve 39 is opened. Since there is a free air passage from the manifold to the actuating cylinders of the air hammers, all the hammers will start to operate immediately upon opening of throttle valve 39. The machine is pushed along at a suitable rate over the surface to be chipped. Since the chippers have a repetition rate of approximately 8000 strokes per minutes, it is obvious that the machine can be moved rather rapidly and still insure a clean chipping job. As was previously discussed, the chisels of the back row are staggered with respect to the front row, whereby a strip of a width defined by the spacing of the back row of chisels will be scaled as the machine is pushed forward over the surface to be scaled. The vehicle frame, the manifold and associated tubing as a protective shield together with the distance the operator is from the actual chipping chisels prevents the scale and dust chipped loose from causing injurious effects to the operator. In this connection, the machine can be further improved by placing a sheet metal hood over the entire chipping mechanism, whereby all chips and dust are prevented from blowing around above the machine where it can endanger the operator.

Obviously, the present machine can be modified in many ways without departing from the spirit and scope of the invention. The vehicle can be easily modified, as well as the mounting configuration of the chippers. Conceivably, too, a vacuum cleaning unit could be attached at the rear of the vehicle whereby the dust and scale

4

can be picked up immediately after it is loosened from the deck. Accordingly, the foregoing description should not be construed as a definition of the invention, but merely illustrative of one form the invention may take. The spirit and scope of the invention are to be limited only by the appended claim.

10 The invention described herein may be manufactured and used by or for the Government of the United States of America for governmental purposes without the payment of any royalty thereon or therefor.

What is claimed is:

15 A machine for scaling steel decks and the like comprising, in combination, a rectangular frame structure, a pair of axles respectively secured to said frame structure along two opposite edges thereof, four wheels journaled on said axles and disposed outside the area enclosed by said frame structure, first and second plate members mounted in said frame parallel to said axles, said plate members being spaced from each other in a direction normal to the axes of said axles, a plurality of pneumatic chipping tools each including a cylinder with a chisel extending from one end thereof, each of said cylinders having a flattened side extending a short distance along the length thereof from the chisel end, said first plate member having an odd number of openings formed therein of a shape conforming to the chisel end of said cylinders symmetrically located with respect to the ends of said first plate member and evenly spaced between centers a distance substantially equal to twice the width of said chisels for accepting a like odd number of said cylinders and maintaining said cylinders in a vertical position, the cutting edges of said chisels thereby being disposed parallel to the said axles and said cylinders constrained from rotation, said second plate member having an even number of similar openings therein symmetrically located with respect to the ends thereof and spaced between centers a distance equal to the spacing between the openings in said first plate for receiving and supporting a like even number of said cylinders, first and second retaining plates mounted to engage the unsupported ends of the cylinders respectively supported by said first and second plate members, and air distribution means mounted on said frame arranged to simultaneously apply compressed air to each of said chipping tools.

DANIEL J. FINN.
